CLAIM

The ornamental design for a combined cover and base for a squeeze tube or the like, as shown and described.

DESCRIPTION

FIG. 1 is a perspective view of a combined cover and base for a squeeze tube or the like showing our design;

FIG. 2 is a fragmentary exploded view;

FIG. 3 is a side elevational view;

FIG. 4 is a side elevational view looking from the right of FIG. 3; and

FIG. 5 is a perspective view of a modified form of our new design.
